UNITED STATES PATENT OFFICE.

JEAN B. VIROLET, OF PARIS, FRANCE.

DESIGN FOR OIL-CLOTH.

Specification forming part of Design No. 7,625, dated August 4, 1874; application filed July 11, 1874.
[Term of Patent 3½ years.]

To all whom it may concern:

Be it known that I, JEAN B. VIROLET, of Paris, France, have invented a new and original Design for Oil-Cloth, of which the following is a specification:

The nature of my design is fully represented in the accompanying photographic illustration, to which reference is made.

The design is intended more particularly for rugs, but it may be applied to other forms, if preferred.

It consists of the landscape A in the middle portion, with figures of a fox and a dog in the foreground, surrounded by the inner border B and the marginal border, composed of the vine and branch shaped figures C D, scrolls E, and beaded lines F.

I claim as my invention—

1. The design for oil-cloth, consisting of the landscape A in the middle or body, containing the figures of a fox and dog, and surrounded by the border B, as shown and set forth.

2. The design for oil-cloth, consisting of the marginal border C D E F, as shown and set forth.

3. The design for oil-cloth, consisting of the landscape A in the middle or body, containing the figures of a fox and dog, and surrounded by the border B, also by the marginal border C, D, E, and F, all as shown and set forth.

J. B. VIROLET.
